J. F. SMITH,
SOUND BOX FOR TALKING MACHINES,
APPLICATION FILED AUG. 24, 1917.

1,302,479.

Patented Apr. 29, 1919.

UNITED STATES PATENT OFFICE.

JAMES F. SMITH, OF ST. LOUIS, MISSOURI, ASSIGNOR OF ONE-THIRD TO ANTHONY F. ITTNER AND ONE-THIRD TO ARTHUR H. BRADLEY, BOTH OF ST. LOUIS, MISSOURI.

SOUND-BOX FOR TALKING-MACHINES.

1,302,479.

Specification of Letters Patent. Patented Apr. 29, 1919.

Application filed August 24, 1917. Serial No. 187,922.

To all whom it may concern:

Be it known that I, JAMES F. SMITH, a citizen of the United States, and a resident of the city of St. Louis and State of Missouri, have invented a new and useful Improvement in Sound-Boxes for Talking-Machines, of which the following is a specification.

The invention relates to sound boxes for talking machines of the type shown in my pending application filed June 22, 1916, Serial No. 105,141; and particularly concerns the stylus lever construction and its adjustable mount.

15 The objects of the invention are the elimination of incidental noises and the improvement of the tone qualities and volume of sound produced. Further objects are to provide for the adjustment of the pitch and 20 the loudness of the tone, and to arrange for the proper mounting of the sound box with relation to the record for satisfactory operation with all kinds of records.

The invention consists in a stylus lever and a spring mounting therefor, permitting adjustment for sensitiveness and amplitude of the vibrations of the stylus. The invention also consists in the details of the connection between the sound box and tone 30 arm as hereinafter described.

Further objects and details of the invention appear in connection with the description of the embodiments of the invention shown in the accompanying drawings; and 35 what the invention consists in is more particularly defined in the appended claims.

In the drawings, wherein the same reference characters designate the same parts in the several views,

40 Figure 1 is a face view of a sound box and tone arm connection embodying one form of the invention;

Fig. 2 is a side view of the same;

Fig. 3 is a cross-section on the line 3—3 45 in Fig. 2, looking in the direction indicated;

Fig. 4 is a plain view of the sound box shown in Fig. 1, the tone arm being shown in central horizontal cross-section;

50 Fig. 5 is a back view of the sound box, showing a portion of the tone arm;

Fig. 6 is an enlarged vertical sectional view of the pivoted portion of the stylus lever;

Fig. 7 is a bottom plan view of the spring 55 support for the stylus lever; and

Fig. 8 is a face view of a modified form of stylus lever, the device being shown in position to play records having lateral undulations.

Referring to the drawings, particularly Figs. 1 to 7, inclusive, the tone arm 10 carries at its outer extremity a sound box 11, which is provided with a diaphragm 12. The sound box is connected to the tone arm by means of an elbow 13, one branch of which is secured in the end of the tone arm and in the other branch of which there is a rotatable hollow stem 14 which carries the sound box. The stem 15 of the sound box 70 is inserted in the hollow stem 14 and retained therein by friction, a paper bushing or gasket being inserted between the two. The hollow stem is secured in the elbow by means of a screw 16, which can be adjusted to permit rotation of the hollow stem and sound box so as to permit the lug 17 on the hollow stem 15 to be positioned in either of the two notches in the adjacent edge of the elbow 13, thereby positioning the lug in the 75 correct position for playing hill and dale or laterally cut records. The withdrawal of the screw 16 permits removal of the sound box. The hollow stem has an opening 14^a in its side near its inner end to provide communication between the sound box and the tone horn in all positions of adjustment.

The lever arm 18 shown in Figs. 1 to 7, inclusive, is tapered upwardly and terminates in a horizontal coil 19. The end of the coil is soldered or otherwise secured to the outer side of the diaphragm 12 at its middle. This forms a flexible connection between the diaphragm and the upper end 90 of the lever 18. The lower portion of the lever is provided with a socket 20 for the stylus 21. The stem of the stylus may be secured in the socket by a knurled screw 22 or any suitable means. The stylus shown 100 in the drawings has an agate point 23, but any suitable point may be used, such as a steel needle for playing all laterally cut records, or a ball or round point for playing hill and dale cut records.

105 The free end of the lever arm is pivotally supported at the outer end of a horizontally disposed flat plate or spring 24. A sup-

porting member 25 is adjustably secured to the rear face of the sound box and has rearwardly and forwardly extending flanges 26 and 27 at its base portion. The rear end 5 portion of the spring 24 is adjustably secured to the rearwardly extending flange 26 of the supporting member 25, and is insulated therefrom by sound insulating blocks 28, arranged one between the flange 10 26 and the top surfaces of the spring 24 and the other below said spring. The spring 24 is adjustable toward and away from the lever arm 18 by means of screws 29 which pass through slots 30 in the spring 24 and 15 screw into the flange 26 of the supporting member. The screws 29 also pass through the insulating blocks 28 and hold them in position. The forwardly extending arm 27 of the supporting member 25 carries a 20 clamp 31 which embraces the spring 24. This clamp 31 is slideable on the flange 27 of the supporting member and spring for adjusting the amplitude of the vibrations of the lever arm 18. The clamp is insulated 25 from the spring 24 by suitable sound insulating blocks 32.

A block 33 is secured to the forward end portion of the spring 24. The lever arm 18 passes through alined openings in the block 30 33 and the spring 24. The lever arm is pivotally mounted in the block 33 by oppositely disposed pivot screws 34. These screws are threaded in the block and project into a sound insulating plug 35 which is mounted 35 in a bore in each of the trunnions 36 on each side of the lever arm 18. The construction shown in Fig. 8 shows a modified form of connection between the upper end of the lever arm 18 and the diaphragm 12. The 40 tapering upper end of the lever arm is wound in the shape of a spiral coil 36, the end of which is soldered or otherwise secured to the diaphragm at its middle.

The sound box construction described in 45 the foregoing specification is capable of playing all makes of records. For playing laterally cut records the sound box is set at a slight angle, and a stylus or needle point used in connection with that particular record is inserted in the lever arm. For 50 playing hill and dale cut records, the sound box is set so as to bring the stylus at right angles to the face of the record and a stylus for playing that particular make of record is inserted in the lever arm. The correct position for playing the two above- 55 mentioned types of records is made positive by the lug on the sound box stem, which coöperates with the two notches in the edge 60 of the branch of the tone elbow, which received the sound box stem.

Other modifications of the form and arrangement of parts may be made in view of the foregoing description of the invention; 65 and the invention is not restricted to the pre-

cise forms and arrangements of the parts shown in the drawings.

I claim the following as my invention:

1. A sound box for a talking machine comprising a diaphragm and a supporting 70 casing, a lever arm connected at one end to said diaphragm and supporting a stylus at its other end, the stylus end of the lever arm being pivotally supported and having a spring connection with said supporting 75 casing, said connection being capable of vertical adjustment with relation to the supporting casing.

2. A sound box for a talking machine comprising a diaphragm and a supporting 80 casing, a lever arm connected at one end to said diaphragm and supporting a stylus at its other end, the stylus end of the lever arm having a vibratory support connected to said supporting casing, and means movably 85 mounted on the supporting casing engaging said vibratory support whereby the amplitude of the vibrations of the same may be varied.

3. A sound box for a talking machine 90 comprising a diaphragm and a supporting casing, a lever arm connected at one end to said diaphragm and supporting a stylus at its other end, the stylus end of the lever arm having a pivotal connection with a vibratory support connected to said supporting casing, and an adjustable clamp slidably 95 arranged on the supporting casing for securing said vibratory support to said casing intermediate its ends.

4. A sound box for a talking machine comprising a diaphragm and a supporting casing, a lever arm connected at one end to said diaphragm and supporting a stylus at its other end, a vibratory support mounted 105 on said supporting casing and arranged for vertical adjustment thereon, the stylus end of the lever arm being pivotally connected to said support and an adjustable yoke slidably mounted on said supporting casing 110 adapted to engage the vibratory support, whereby the amplitude of the vibrations of said lever arm can be controlled.

5. A sound box for a talking machine, comprising a diaphragm and a supporting 115 casing, a lever arm connected at one end to the diaphragm of the sound box and supporting a stylus at its other end, a vertically adjustable support secured to the sound box, a vibratory member, one end being adjustably secured to the vertically adjustable support and the other free end being adapted to pivotally support the lower portion of the stylus arm, and a clamp for securing the vibratory member to the vertically adjustable support, said clamp being arranged to slide along the adjustable support, whereby the amplitude of the vibrations of the lever arm can be controlled.

6. A sound box for a talking machine 120

comprising a diaphragm and a supporting casing, a lever arm having one end connected to said diaphragm, a stylus connected to the lower end of said lever arm, a vertically 5 adjustable support secured to the sound box having a horizontally disposed base portion, a flat spring located beneath said base portion and having one end secured thereto, means for adjusting said spring toward and 10 away from the lever arm, the opposite free end of said spring being arranged to pivotally support the lower portion of the lever arm, and a clamp for securing the spring to the base portion of the vertically adjustable 15 support, said clamp being arranged for movement toward and away from the lever arm.

7. A sound box for a talking machine com-

prising a diaphragm and a supporting casing, a vibratory support connected to said supporting casing and arranged for bodily adjustment in both horizontal and vertical directions, means movably mounted on the supporting casing engaging said vibratory support for varying the amplitude of the vibrations of said vibratory support, and a stylus lever pivotally mounted on said vibratory support and supporting a stylus on its lower arm, the upper arm of said stylus lever terminating in a wire-like member of substantially uniform section coiled into a helical spiral, said helical spiral being connected to the diaphragm of the sound box.

Signed at St. Louis, Missouri, this 18th day of August, 1917.

JAMES F. SMITH.
